IMPACT OPERATED RELEASE MECHANISM

Theodore H. Carpenter, New London, Conn., assignor to United States of America, as represented by the Secretary of the Navy

Application June 27, 1944, Serial No. 542,415

9 Claims. (Cl. 9—8)

This invention relates in general to automatically operated release mechanisms and, in particular, to such a mechanism for automatically releasing a device or object such as a hydrophone from a casing as the casing strikes the water after being suitably launched such as by parachuting from aircraft.

The principal objects are to provide a release mechanism of the type described which will (1) protect the releasable device against damage at the time of impact with the water; (2) be totally enclosed within the casing; and (3) be positive in action and yet fully protected against premature operation.

Other objects of the invention will become more apparent from the following description and the accompanying drawing, which illustrates a preferred embodiment of the invention as applied to the releasable hydrophone in the radio-sonic buoy described in application Serial No. 555,154, filed September 21, 1944. However, it will be understood that the invention may be used equally as well to release other objects. In the drawing:

Fig. 1 is a perspective view, partially broken away, of the release mechanism attached to the lower end of the buoy casing, showing the relative positions of the mechanism and the hydrophone which is to be released;

Fig. 2 is a perspective view of the operating portion of the device; and

Fig. 3 is a vertical sectional view of the device as assembled in the buoy.

Referring now to the drawing, in which like parts are identified by like reference numerals, the device consists generally of a fixed casting, or frame, 10 with the operating mechanism 12 contained therein. In the embodiment shown, the frame is secured to the lower end of the buoy case 14 and forms part of the chamber holding the hydrophone 16 to be released. The upper end of the hydrophone bears against the upper end of the chamber as shown in application Serial No. 535,170, filed May 11, 1944. The frame 10 also serves as part of the weight necessary to cause the container to float in water in the proper position.

The operating mechanism 12 is shown in detail in Fig. 2. It consists of a pressure plate 18, one end of which is cut away to form a slot 20. A shaft 22 is secured to the underside of the plate 18 across the slot 20 and pivotally carries a latch 24 in the slot. The free end of the latch comprises a hook 26 and an ear 28. A tension spring 30 extends from the ear 28 to a spring anchorage 32 at the opposite end of the pressure plate 18.

The frame 10 as shown in Fig. 3 has a slot 34 formed at one side on its inner surface and a socket or recess 36 at the opposite side to receive the ends of the pressure plate 18. The hook 26 of the latch 24 engages with a lip 38 on the inner side of the frame. A compression spring 40 is interposed between the plate 18 and the hydrophone 16 to hold the plate in the latched position, resiliently mount and cushion the hydrophone from the effect of impact, and permit the plate to approach the hydrophone and release the latch 24 on impact. The compression spring 40 is supported on a channel-shaped bracket 42 fastened to the plate 18 to clear the tension spring 30.

Operation of the device is as follows: The buoy or other device with which the present device is used falls into the water in the general position shown in Fig. 3 after being launched by any suitable means. As it strikes the water, the impact of the water on the underside of the pressure plate 18 forces it up against the compression of the spring 40, and the plate pivots about its end in the recess 36. This lifts the end of hook 26 clear of lip 38, and the tension spring 30 then pulls the latch 24 clear of the frame, pivoting on shaft 22.

As the downward velocity of the buoy diminishes, the water pressure on the plate 18 decreases rapidly until it is no longer greater than the strength of the compression spring 40, at which time this spring forces the whole assembly out of the bottom of the frame. The hydrophone to be released is now free to fall out of the chamber under the influence of gravity.

In conclusion, it will be understood that the invention may be applied equally as well to the similar release of objects other than hydrophones and from other types of enclosing casings.

Furthermore, it will be apparent that the particular construction and arrangement of elements described is illustrative only and that changes may be made therein without departing from the spirit and scope of the invention as defined in the appended claims.

Having thus fully described my invention, I claim:

1. A casing adapted to be launched into water such as from aircraft, said casing being open at the lower end, a device within said lower end, support means for releasably securing said device within said casing, and means operable upon impact of said support means with the water to release said support means whereby said device will be free to drop out of said casing.

2. A casing adapted to be launched into water

such as from aircraft, said casing being open at the lower end, a device within said lower end, support means for releasably securing said device, resilient means disposed between said support means and said device for resiliently mounting the latter, and means operable upon impact of said support means with the water to release said support means whereby said device will be free to drop out of said casing.

3. A casing adapted to be launched into water such as from aircraft, said casing being open at the lower end, a device within said lower end, a plate member extending transversely across the lower end of said casing, securing means for said plate member, resilient means disposed between said plate member and said device for resiliently mounting the latter, and means operable upon impact of said plate member with the water for releasing said plate member from its said securing means whereby said device will be free to fall out of said casing.

4. A casing adapted to be launched into water such as from aircraft, said casing being open at the lower end, a device within said lower end, a plate member extending transversely across the lower end of the casing, means including latch means for securing said plate member in place, resilient means disposed between said plate member and said device for resiliently mounting the latter, and means operable upon impact for releasing said plate securing latch means whereby said device will be free to drop out of said casing.

5. In a buoy adapted to be launched into water such as from aircraft, said buoy including a casing open at its lower end and a hydrophone therein, support means for releasably securing said hydrophone within said casing, and means operable upon impact of said support means with the water to release said support means whereby said hydrophone will be free to drop out of said casing.

6. In a buoy adapted to be launched into water such as from aircraft, said buoy including a casing open at its lower end and a hydrophone therein, a plate member extending transversely across the lower end of said casing, securing means for said plate member, resilient means disposed between said plate member and hydrophone for resiliently mounting said hydrophone, and means

operable upon impact of said plate member with the water for releasing said plate member from its said securing means whereby said hydrophone will be free to drop out of said casing.

7. In a buoy adapted to be launched into water such as from aircraft, said buoy including a casing open at its lower end and a hydrophone therein, support means for releasably securing said hydrophone within said casing, resilient means disposed between said support means and said hydrophone for resiliently mounting said hydrophone, and means operable upon impact of said support means with the water to release said support means whereby said hydrophone will be free to drop out of said casing.

8. In a buoy adapted to be launched into water such as from aircraft, said buoy including a casing open at its lower end and a hydrophone therein, a plate member extending transversely across the lower end of said casing, means including latch means for securing said plate member in place, resilient means disposed between said plate member and hydrophone for resiliently mounting said hydrophone, and means operable upon impact of said plate member with the water for releasing said plate securing latch means whereby said plate and hydrophone will be free to drop out of said casing.

9. In a buoy adapted to be launched into water such as from aircraft, said buoy including a casing open at its lower end and provided with a recess on one side and a lip opposite thereto, and a hydrophone within the lower end of said casing, a plate extending transversely across the lower end of said casing, said plate having a hook member pivotally mounted at one end of said plate and engaging said lip, the other end of said plate being received in said recess, spring means urging said hook member away from said lip, and resilient means disposed between said plate and hydrophone for resiliently mounting said hydrophone, whereby upward motion of said plate initiated upon its impact with the water will raise said hook member above the top of said lip allowing said spring means to disengage said hook member therefrom and the hydrophone to fall out of said casing under the restoring force of said resilient means.

THEODORE H. CARPENTER.
